ETHYLENE OXIDE STERILIZING AGENT
 Robert A. Fulton, Silver Spring, and Edward O. Haenni,
 Bethesda, Md., assignors to the United States of America
 as represented by the Secretary of Agriculture
 No Drawing. Filed Aug. 22, 1958, Ser. No. 756,739
 6 Claims. (Cl. 167—39)

A non-exclusive, irrevocable, royalty-free license in the invention herein described, throughout the world for all purposes of the United States Government, with the power to grant sublicenses for such purposes, is hereby granted to the Government of the United States of America.

This invention relates to gaseous disinfecting and sterilizing agents which will effectively disinfect heat- or water-sensitive materials, such as, surgical equipment and the like, at room temperatures and which will also effectively disinfect enclosed spaces such as containers, rooms, aircraft and the like, and their contents. More particularly, this invention relates to gaseous disinfecting and sterilizing agents which are stored as liquids under pressure in containers and which may be released into the atmosphere through a valve in the container.

It is known that ethylene oxide, which is a gas at room temperature (B.P. 10.7° C.), is an extremely powerful germicide and is effective when released into the atmosphere in a closed room or cabinet to kill bacteria and spores.

It has been proposed to package liquefied ethylene oxide as an 11 to 19% solution in liquefied Freon 12 (dichlorodifluoromethane) under pressure in a container similar to those commonly in use to disperse insecticide aerosols and to release the desired amount of gas for sterilizing purposes as needed, the Freon 12 serving as a propellant for the ethylene oxide. However, ethylene oxide is an extremely inflammable substance and in concentrations of about 19% in dichlorodifluoromethane or even somewhat lower may produce explosive vapors. In concentrations of 11 or 12% by weight (i.e., 26.5 or 28.5 mole percent, respectively) explosion danger is practically non-existent while the disinfectant properties are retained.

However, since liquefied Freon 12 exerts a pressure of about 85 p.s.i. the preparation must be put up in a high pressure container such as the ICC 9 or ICC 40 to meet Interstate Commerce Commission regulations. Such containers are commercially available for packaging insecticides which are to be used in the form of aerosols, but are relatively high in cost.

It is an object of the present invention to provide an ethylene oxide-propellant solution of effective concentration which will produce a non-explosive vapor and which may be packaged in Interstate Commerce Commission approved low pressure containers. A further object of this invention is to provide a liquefied ethylene oxide-propellant mixture which will have a pressure not exceeding 40 p.s.i. Other objects and advantages will become apparent to those skilled in the art from the following description.

In accordance with the present invention liquefied ethylene oxide is dissolved in a propellant which comprises a mixture of Freon 12 and a suppressor for the vapor pressure of Freon 12, such as Freon 11 (trichlorofluoromethane). These substances are also commercially available under the names Genetron-12 and Genetron-11, respectively. Freon 11, having a high boiling point and lower vapor pressure than Freon 12, serves as a suppressor, thus reducing the pressure inside the container. Other suppressors which can be used in place of Freon 11 or in combination therewith are:

2

Freon 21 (dichlorofluoromethane),
 Freon 112 (tetrachlorodifluoroethane),
 Freon 113 (trichlorotrifluoroethane),
 Freon 114 (dichlorotetrafluoroethane),
 5 Methylene chloride (dichloromethane),
 Methyl chloroform (1,1,1-trichloroethane), and
 Methyl bromide.

Low pressure containers are commercially available and are less expensive to manufacture, thus materially reducing the total cost of the finished product.

A preferred formulation comprises a 12% solution of liquefied ethylene oxide in a mixture of equal parts of liquefied Freon 11 and Freon 12. The latter mixture is commercially available. Parts and percentages referred to are by weight of the components. Thus, such a composition contains 12% by weight of ethylene oxide and 44% by weight each of Freon 11 and 12. In terms of mole percentages, these proportions are 28.5%, 33.48%, and 38.02%, respectively. For a composition containing 11% by weight of ethylene oxide and the said Freon mixture containing equal parts of Freon 11 and 12 (i.e., 44.5% by weight each of the two Freons), the corresponding mole percentages would be 26.5% ethylene oxide, 34.5% Freon 11, and 39.0% Freon 12.

25 The invention is further illustrated by the following examples:

Example 1

30 940 grams of liquefied ethylene oxide, which had previously been distilled to purify it, were carefully transferred from a supply cylinder to a weighed evacuated cylinder provided with a valve. The valve was shut after the desired amount of ethylene oxide had been transferred and the supply cylinder disconnected. A second supply cylinder containing a liquefied mixture of equal parts of Freon 11 and Freon 12 was then connected to the evacuated cylinder containing the 940 grams of ethylene oxide and 6896 grams of the Freon mixture were transferred. The evacuated cylinder then contained 7836 grams of a 40 solution of ethylene oxide in the Freon 11-Freon 12 mixture in which the concentration of ethylene oxide was 12% and the two Freons were each present in the amount of 44%. This mixture was non-explosive.

359.2 grams of the above solution (equivalent to 50 45 ml. ethylene oxide) were transferred to each of a number of commercially available 12 oz. low pressure cans. These cans were tin-lined with no exterior enamel, were provided with nylon gaskets, lambs wool filters and had 0.030" orifices.

50 The pressure within the cans was about 38 p.s.i. thus complying with Interstate Commerce Commission regulations for low pressure containers.

Example 2

55 The following experiment was carried out to demonstrate the sterilizing power of the 12% ethylene oxide composition described above:

Miscellaneous articles of clothing, including shirts, 60 trousers, underwear, sox, hats, overcoats, and shoes were put into polyethylene bags, each six mils in thickness. Cotton cloth patches carrying the spores of *B. subtilis* var. niger (*B. globigii*) were also put into the bags and distributed among the clothing.

65 A single shot capsule provided with a snap-off top and containing the 12% ethylene oxide solution described in Example 1 was then put into each bag and the bags were sealed. The capsules were opened by breaking off the tops, thus releasing the ethylene oxide-Freon mixture as a gas inside the bags. After 6 to 8 hours the bags were opened and the spore-laden cloth patches were examined and incubated.

It was found that all of the spores had been killed.

We claim:

1. A noninflammable sterilizing agent comprising a mixture of about from 11 to 12% by weight of ethylene oxide and the balance being a mixture of dichlorodifluoromethane and a member of the group consisting of dichlorofluoromethane, tetrachlorodifluoroethane, trichlorotrifluoroethane, dichlorotetrafluoroethane, dichloromethane, 1,1,1-trichloroethane, methyl bromide, and mixtures thereof.

2. A sterilant comprising a mixture of ethylene oxide, dichlorodifluoromethane, and trichloromonofluoromethane in the proportions of 26.5 mole percent ethylene oxide, 39.0 mole percent of dichlorodifluoromethane, and 34.5 mole percent of trichloromonofluoromethane.

3. A sterilant comprising a mixture of ethylene oxide, dichlorodifluoromethane, and trichloromonofluoromethane in the proportions of about 26.5 to 28.5 mole percent of ethylene oxide, 38.02 to 39.0 mole percent of dichlorodifluoromethane, and 33.48 to 34.5 mole percent of trichloromonofluoromethane.

4. A noninflammable sterilizing agent comprising about 12% ethylene oxide, about 44% dichlorodifluoromethane and about 44% trichlorofluoromethane.

5. A noninflammable sterilizing agent comprising a liquid mixture of about 12% ethylene oxide, about 44% dichlorodifluoromethane, and about 44% trichlorofluoromethane.

6. An article of manufacture comprising a liquid sterilizing agent composed of about 12% ethylene oxide, about 44% dichlorodifluoromethane, and about 44% trichloro-

fluoromethane packaged in a container provided with a valve adapted to release said disinfectant as a gaseous mixture into the atmosphere.
